[57] CLAIM

The ornamental design for a horseshoe for a hind hoof, as shown and described.

DESCRIPTION

FIG. 1 is a front elevational view of a horseshoe for a hind hoof showing my new design;

FIG. 2 is a bottom plan view thereof;

FIG. 3 is a fragmentary side elevational view taken along line 3—3 of FIG. 2;

FIG. 4 is a side elevational view, the opposite side being a mirror image of the side shown;

FIG. 5 is a cross sectional view taken on line 5—5 of FIG. 3;

FIG. 6 is a front elevational view of a second embodiment of the horseshoe for a hind hoof shown in FIG. 1;

FIG. 7 is a bottom plan view of FIG. 6;

FIG. 8 is a fragmentary side elevational view taken along line 8—8 of FIG. 7;

FIG. 9 is a side elevational view, the opposite side being a mirror image of the side shown; and

FIG. 10 is a cross sectional view taken on line 10—10 of FIG. 8.
